UNITED STATES PATENT OFFICE.

JOHN BYRON CASSELMAN, OF OAKLAND, CALIFORNIA.

RAILWAY-SIGNAL.

1,116,799.

Specification of Letters Patent. Patented Nov. 10, 1914.

Application filed January 31, 1914. Serial No. 815,635.

To all whom it may concern:

Be it known that I, JOHN BYRON CASSELMAN, a citizen of the United States, residing at Oakland, in the county of Alameda 5 and State of California, have invented certain new and useful Improvements in Railway-Signals, of which the following is a specification.

This invention relates to improvements 10 in automatic train signaling devices and more particularly in the construction of the semaphore and associated parts used on those signal systems employing an auxiliary or tripper arm to engage a valve arm or 15 other device for automatically stopping the train in case the signal is passed.

The principal object of this invention is to provide a tripper arm, which will operate from the stop position to clearance position, and from clearance position to stop position without any change in the position of the semaphore arm and yet provide 20 means so that the tripper arm can never be in the stop position, the position that would 25 engage the car valves, with the semaphore arm in the proceed position.

Another object is to allow the semaphore arm to assume the horizontal, or stop position as soon as the first truck of train has 30 passed the signal and hold the tripper device in the clearance position for any determined length of time, as until the last car truck has passed the signal. With the present system the semaphore arm and tripper 35 are held in the proceed position until the train is a determined distance past the semaphore. With this arrangement a switch might be opened, or a rail broken, or a train occupy this distance and the semaphore arm would indicate a wrong condition 40 of the section of track of which the semaphore governs. With my improvement there could be no danger of such an occurrence for the semaphore arm would be 45 brought to its stop position by the occupying train while the tripper arm is retained above the stop position until after the train has passed the signal. By being able to control the movement of this tripper device in 50 dependent of the semaphore arm while the semaphore arm is in the stop position allows the operating of this tripper device from any "central source of control by electrical means", which would be especially 55 serviceable when it is necessary to

run trains in the opposite direction to which the signal was to be operative, a condition often met with when one track is undergoing repairs.

The use of this device would decrease the 60 costs of car valve equipment, for the tripper device being clear of the car valves when running against the "current of traffic" would lessen the construction cost of a proper valve to take care of the brake application. The car valve need only be constructed to take care of the application of brakes when they come in contact with this tripper device, while at present they are 65 designed to apply the brakes when struck in one direction and when struck in opposite direction to receive the blow but not to apply brakes. This complicates the construction of satisfactory valves and by constructing valves that apply the brakes irrespective of the direction in which the train 70 is running when struck would allow of the car valves being placed on either side of cars and the tripper devices could be located on either side of track. In a good many 75 instances it is almost impossible to locate all semaphores uniformly on the right or 80 the left of the right of way.

With these and other objects in view my invention consists in certain new and novel 85 features which will be hereinafter described and claimed.

Reference is to be had to the accompanying drawings forming a part of this specification wherein;

Figure 1 is a partly broken view in front elevation of a semaphore signal constructed in accordance with my invention. Fig. 2 is a view in section on X—X Fig. 1. Fig. 3 is an enlarged horizontal sectional view 95 through the top of the signal standard. Fig. 4 is a view in section of the glass valve which is broken by the tripper arm of my signal when a train attempts to pass the same when set at danger. Fig. 5 is a view 100 in section of the mechanism valve for accomplishing the same purpose.

Denoting corresponding parts by the same numerals of reference, 1 denotes a hollow standard having the enlarged base 2 wherein 105 is located the mechanism for operating the signal and which it is not deemed necessary to illustrate as the same forms no part of this invention. Adjacent the top of pole 1 is a pair of laterally extending lugs 3, be-

tween which is an opening 4, providing access to the interior of the pole. Pivotally mounted in the lugs 3 is a pintle 5 having keyed thereon between the lugs 3 a lever arm 6, which extends through opening 4 and within the pole is pivotally attached to the operating rod 7, the lower end of which is attached to the operating mechanism. Pivotally mounted on the pintle 5 is the semaphore bracket 8, to which is attached the indicating arm 9 and adjacent this bracket a lens segment 10 is keyed to the shaft and is provided with a segment slot 11. Bracket 8 is provided with a laterally extending pin 12, which extends into the slot 11 providing a driving connection for the semaphore arm. The bracket 8 is also provided with a rearwardly extending lug 13 which contacts with a stop pin 14 in the post 1 and serves to prevent the indicating arm from dropping below the horizontal position.

The lens segment is provided with lenses 15, 16, and 17, the first being of a color to indicate proceed, the second caution, and the third stop. It will also be noted that lens 17 is elongated for the purpose which will be later described.

Below the semaphore is pivotally mounted an arm 18, which under certain conditions contacts with the device 19 on the car roof 19' and by contact therewith automatically brings the train to a stop. The device 19 may be a lever operated valve and so releases the train line air pressure or a glass tube, which is broken and accomplishes the same result. The arm 18 is connected to the lens plate 10 by a link 20, which is pivotally mounted on a pin 21 projecting from the plate 10 and a pin 22 adjustable on the arm 18. A lamp 23 is mounted on a suitable bracket 24 so as to show through the various lenses.

In operation four positions of rest are provided for pintle 5 and its attached parts; 1st, lens 15 in front of lamp 23, which throws arm 9 in an upward vertical position and arm 18 close to the pole; 2nd, lens 16 in front of lamp 23, arm 9 and 18 in a position approximately 45 degrees to the pole; 3rd, the position as shown in Fig. 1 with the lower part of lens 17 in front of the lamp the semaphore arm 9 in a horizontal position and arm 18 somewhat above the top of device 18; 4th, the upper part of lens 17 in front of lamp 23 and the lens plate and arm 18 occupying the position shown in dotted lines in Fig. 1. During the movement to assume the last position arm 9 remains stationary by reason of lug 13 engaging pin 14 and also while the pin 12 moves along slot 11.

While I have shown the preferred embodiment of my invention it will of course be understood that changes may be made in

minor details and form of construction without departing from the spirit thereof.

65

What I claim is:—

1. A signal comprising a pivotally mounted tripper arm, means operatively connecting said tripper arm with the actuating mechanism of the signal, a pivotally mounted semaphore arm, a slotted connection between the actuating mechanism of said signal and said semaphore arm, a stop to limit the movement of said semaphore arm and allow the further movement of said tripper arm after said semaphore arm indicates stop.

2. In a signal comprising the combination of a suitable supporting standard, a shaft pivotally mounted therein adjacent the top thereof, an operating lever keyed to said shaft, a semaphore arm pivotally mounted on said shaft, a lens carrying segment keyed to said shaft, a segmental slot in said lens segment a pin carried by said semaphore arm and projecting into said slot, a tripper arm pivotally mounted below said semaphore arm and a link connecting said tripper arm and said lens segment.

3. A signal comprising the combination of a supporting standard, a shaft pivotally mounted therein, an operating lever keyed thereto, a semaphore arm pivotally mounted on said shaft, a tripper arm pivotally mounted on said standard below said semaphore arm and in the same place, a stop lug carried by said semaphore arm adapted to engage a pin carried by said standard for limiting the downward movement of said semaphore arm, a lens segment keyed to said shaft, a link pivotally connected thereto, and to said tripper arm, a segmental slot in said lens segment, a pin carried by said semaphore arm projecting into said slot and so positioned as to allow the further movement of said lens segment and connected tripper arm after the movement of the semaphore arm has been arrested by said stop.

4. A signal comprising a pivotally mounted semaphore arm, a lens segment operatively connected to the actuating mechanism of said signal, a pivotally mounted tripper arm, a link connecting said tripper arm and said lens segment, a stop limiting the movement of said semaphore arm, and a loose connection between said semaphore arm and said lens segment to permit the further movement of said segment and attached tripper arm after the semaphore arm indicates stop.

In testimony whereof I affix my signature in presence of two witnesses.

JOHN BYRON CASSELMAN.
